UNITED STATES PATENT OFFICE.

FREDERICK W. EBELING, OF NEW YORK, N. Y., ASSIGNOR TO SUBMARINE DEVICES CORPORATION, A CORPORATION OF DELAWARE.

METHOD OF AND APPARATUS FOR RAISING SUBMERGED VESSELS.

Application filed November 12, 1920. Serial No. 423,576.

To all whom it may concern:

Be it known that I, FREDERICK W. EBELING, a citizen of the United States, residing at New York, in the county of New York and State of New York, have invented certain new and useful Improvements in Methods of and Apparatus for Raising Submerged Vessels, of which the following is a specification, reference being had there-
10 in to the accompanying drawing.

This invention relates to the salvaging or raising of submerged vessels, and has to do more particularly with that system in which the vessel is raised by giving it buoyancy by the expulsion of water therefrom by air pressure.
15

In the operation of raising vessels by this system, under certain methods of procedure it is the practice to send a diver down to 20 the submerged vessel who closes up the hatchway or other communication of the hold with the outside and then connects a pipe with the water filled hold for the introduction of compressed air, which pipe leads upwardly to the surface of the water where it is connected with a suitable air 25 compressing apparatus. The effect of the air thus forced into the hold is to expel the water therefrom through the opening or

30 hole stove in the hold, thereby reducing the water level in the hold and replacing the water with air. This will give buoyancy to the vessel and cause it to rise. As the vessel rises, the hydrostatic pressure of the 35 water acting on the outside of the vessel decreases, and the pressure of air within the hold will over balance the hydrostatic pressure acting on the deck, so that the latter will be subjected to severe stresses by the internal air pressure, with the result that it will 40 be seriously strained or otherwise injured, and it is frequently ruptured.

The aim of the present invention is to 45 overcome this liability of the deck to injury, and the invention consists of an improved method characterized by the automatic relief of the air pressure in the hold as the hydrostatic pressure decreases on the rise of the vessel; and in the means for carrying

said method into effect, which will be fully 50 set forth in the description to follow, and the novel features of which method and means will be defined in the appended claims.

In the accompanying drawings: 55
Fig. 1 is a cross section of a submerged vessel equipped with means of one form for carrying my improved method into effect.

Fig. 2 is a longitudinal section of the same. 60
Fig. 3 is a top plan view looking down into the hold and showing the trunk applied thereto for carrying my invention into effect, certain parts being broken away to expose other parts to view.

Fig. 4 is a perspective view of the trunk 65 on a reduced scale.

Fig. 5 is a vertical transverse section through one side of the trunk and the adjacent portion of the hatch coaming and deck on an enlarged scale, showing the devices 70 of Fig. 1 for fastening the trunk in place.

Fig. 6 is a similar view showing devices of a different form for securing the trunk in place.

Fig. 7 is a transverse section through the 75 side of the vessel showing how the air pipe for introducing air under pressure is applied to the ventilator.

Fig. 8 is a diagrammatic view of a vessel 80 in transverse cross section showing how my improved method is carried into effect in connection with a vessel having upper and lower holds and an intervening deck.

Referring to the drawings: 85
Referring particularly to Figs. 1 to 5, 1 designates the hull of a vessel having a hold 2 covered by a deck portion 3 containing the usual hatchway 4 leading into the hold, the said hatchway being surrounded by the usual hatch coaming 5 extending upwardly 90 from the deck. 6 designates a casing in the form of a trunk rectangular in cross section and open at its two ends, which trunk is positioned in the hatchway and depends a substantial distance into the vessel's hold, 95 and is firmly fastened rigidly in place at its upper end. In the construction shown in Figs. 1 to 5 the trunk is provided at its

upper end with a lateral extension or flange 7 projecting outwardly therefrom and over the upper end of the hatch coaming, a packing 8, preferably of wood, being applied 5 to the underside of the flange and bearing on the upper end of the coaming to form a substantially air-tight joint at this point. The trunk is fastened in place in this instance by means of a number of vertical 10 bolts 9 extending through holes at intervals in the flange 7 and downwardly alongside the trunk, between it and the interior of the hatch coaming. The lower ends of these bolts are passed through holes in the 15 inner ends of horizontal plates 10 which are provided at their outer extremities with upturned hooks engaging around a horizontal flange 11 projecting outwardly from the lower end of the hatch coaming. The upper 20 and lower ends of the bolts are threaded and on these threaded ends, nuts 12 and 13 are screwed, which being turned up will draw the packing on the flange tightly against the upper end of the hatch coaming 25 and thereby secure the trunk firmly in place in the hold, sealed air-tight at its upper end.

In carrying my improved method into effect with an equipment of this character to raise a submerged vessel whose hold has 30 become filled with water, which for instance has entered the hold through a hole 14 stove in the hull of the vessel, the trunk 6 is lowered to the submerged vessel and divers descend and apply the same to the hatchway 35 as shown in Fig. 1, after first closing other communications of the hold with the outside, such as funnels, etc. Provision is made for forcing air under pressure into the water-filled hold as by a pipe 15 entering 40 through the side of the trunk as shown by full lines in Fig. 1, or a pipe 16 extending downwardly within the trunk and provided with an upturned end terminating near the deck as shown by dotted lines in Fig. 1, or 45 by means of a pipe 17 passed through the funnel 18 and fastened in place by a cement packing 19 as shown in Fig. 7. The air pipe, whichever form may be used, is extended upwardly to the surface of the water where 50 it may be connected with a suitable air compressing apparatus X, illustrated conventionally in Fig. 1. Air under pressure is now forced into the hold, and it will act to expel the water therefrom through the hole 55 in the vessel's hull, and the water level in the hold will be lowered until sufficient air has replaced the water to give the vessel the necessary buoyancy to cause it to rise. At this time the water level in the hold is above 60 the lower end of the depending trunk, and the water fills the trunk and a portion of the hold and surrounds the outside of the vessel, and it therefore acts with a certain hydrostatic pressure on the deck of the vessel, as well as against the body of compressed

air within the hold. As the vessel rises, the hydrostatic pressure on the deck of course decreases, as does also that acting within the hold, and as the air pressure within the hold is maintained to keep the water out and preserve the vessel's buoyancy, this internal air pressure will at a certain point in the rise of the vessel become higher than the hydrostatic pressure, and unless means were provided to prevent it, the deck would be injured or ruptured by the over balancing air pressure. The trunk 6 however prevents such a result, as it affords a passage-way for the escape of the air from the hold when the hydrostatic pressure acting through the 70 trunk is so far reduced by the rise of the vessel as to be overcome by the air pressure within the hold, this escape of the air through the trunk being of course gradual and acting to relieve the pressure of the volume of air above the water level within the hold. The effect is therefore to automatically relieve the pressure in the hold in accordance with the reduction of hydrostatic pressure due to the rise of the vessel. In 75 this way, strain on or rupture of the deck or walls of the hold will be effectually prevented.

In order to facilitate the positioning of the trunk in the hatch coaming when the former is lowered to the submerged vessel, the trunk is provided on its four sides with a number of upright guiding plates or brackets 19 whose lower portions are beveled or inclined inwardly as at 19^a, and whose upper portions are vertical as at 19^b. As the trunk approaches its final position, the inclined portions 19^a of the brackets by cooperating with an inwardly extending flange 20 on the interior of the hatch coaming, will act to guide the trunk in its descent, and when the latter reaches its final position as shown in Figs. 1 and 5, the vertical portions of the brackets will stand opposite the edge of the flange and thus center and determine 80 the proper final position of the trunk.

The devices for fastening the trunk in place will be of a form to meet the different constructions of hatch coamings as they exist in different types of vessels. For instance the hatch coamings of certain types of vessels are constructed as shown in Figs. 1 and 5, while others are provided with a horizontal flange 21 as shown in Fig. 6. In this latter construction instead of the long bolts 9 and the horizontal plates 10 employed for fastening the trunk in place as shown in Figs. 1 and 5, short bolts 22 are employed as shown in Fig. 6, which extend through holes in the outer edges of the flange on the 85 trunk and downwardly some distance, and are provided on their lower ends with inwardly turned hooks 22^a engaging beneath the underside of the flange 21, these bolts being threaded at their upper ends and pro- 90

vided with nuts 23 which when screwed down against the flange, will draw the same downwardly and seat the packing on the flange tightly against the upper end of the 5 coaming.

It is obvious of course that other means may be employed for fastening the trunk in place so that it will depend into the vessel's hold; and it is obvious also that provision

10 may be made for the introduction of compressed air by means other than the particular examples shown and above described, the essential requirements in this respect being that the trunk will be fastened firmly in 15 place within the hatch coaming, and sealed against the escape of air around the outside of the same from the interior of the hold.

In equipping vessels which have superposed holds separated by an intervening 20 deck or decks, in order to carry out my improved method, a trunk is applied to the hatchway of each deck as shown in Fig. 8 in substantially the same manner as the application of the trunk as heretofore described, 25 an upper trunk 24 being applied to the hatchway of the upper deck, and a lower trunk 25 being applied to the hatchway of the lower deck; and compressed air is admitted to the two hatchways independently 30 as shown by the two pipes 26 and 27, or by the other arrangements heretofore described. The relief of the air pressure within the holds however will be effected automatically under the same principle of operation as that 35 before described, with the result that the pressure acting against the underside of the decks will be automatically relieved by the reduction of the hydrostatic pressure of the water as the vessel rises, and rupture or 40 other injury to the decks will be prevented.

It will be understood that the depth of the trunk or its amount of penetration into the hold in any particular case, will depend upon the depth of submergence of the vessel 45 and the degree of buoyancy necessary to cause it to rise. For instance if the deck of the vessel is twenty feet below the surface of the water it will be subject to an external pressure of 8.8 lbs. to the square inch, and 50 if a trunk of a depth of ten feet say is employed, an air pressure within the hold of 13.2 lbs. to the square inch will be necessary to lower the level of the water to a point where the vessel will be given the necessary 55 buoyancy to cause it to rise. The deck will be subjected on its inside to a net or effective pressure of 13.2 lbs. — 8.8 or 4.4 lbs. to the square inch, which pressure while being sufficient to keep the water level down to a 60 point to maintain the buoyancy, will not be great enough to strain or otherwise injure the deck. Now as the vessel rises, the hydrostatic pressure on the outer side of the same decreases, and that acting against the body 65 of air in the hold also decreases, with the re-

sult that the trapped air will escape around the lower edge of the trunk, and in this manner will always balance the water pressure at said lower edge. Consequently the effective pressure of air on the inside of the deck will 70 remain constant, since the actual pressure in the hold is automatically reduced in proportion to the reduction of hydrostatic pressure acting on the outside of the deck.

It will be understood that as shown in Fig. 75 2 the different holds or compartments extending throughout the length of the vessel will be treated in the same manner as above described, that is, each of said holds, or such a number of them as will be necessary to 80 treat in order to give buoyancy to the vessel, will have the trunks applied and the compressed air introduced as shown.

While in the foregoing description and accompanying drawings I have set forth my 85 invention as regards the particular method of procedure, and the detailed form of the apparatus, which I prefer to adopt, it will be understood that these details may be variously changed, both as regards the method 90 and apparatus, without departing from the limits of the invention; and it will be understood that the invention is not limited as regards either phase of the invention except in so far as such limitations are specified in 95 the claims.

While in the foregoing description and accompanying drawings the invention has been shown as applied to the raising of vessels which have been damaged by having a 100 hole stove therein, it is obvious that the invention is not restricted to such conditions as the method may be carried out just as effectively and under the same principle of operation in a case where there has been no 105 injury to the hold or hole stove in the same. In such case, the air pressure will act to force the water out through the trunk or trunks, and the relief of the trapped air in the hold will take place in a manner similar 110 to that hereinbefore described.

It is to be noted that the trunk 6 is of substantial and extended cross sectional size and follows generally in its contour, the cross sectional contour and size of the hatchway. This is an important feature of my 115 invention both as regards the method involved and the mechanical construction. When so formed and constructed, the trapped air within the hold is permitted 120 great freedom of escape through the trunk, and in great volume. As a result, in the event that the vessel rises suddenly, as it may do because of being held by some obstruction or the sticky character of the soil in 125 which it may be embedded, the hydrostatic pressure acting on the deck will be correspondingly suddenly reduced and unless means were provided for permitting the air in the hold to rapidly escape in large volume, 130

there would be such accumulation of pressure on the interior of the vessel as would either rupture or injure the deck. It is desirable therefore that the trunk be of large cross sectional area in order to permit the internal pressure to be quickly equalized under the conditions mentioned. Furthermore, where the trunk follows generally the contour of the hatchway, there will be no need to construct a special covering for the hatchway, as there would be if the relief passage were of restricted area in cross section as constituted for instance by a pipe. Such special covering would be very difficult if not impossible to construct and fasten in place in such manner as to withstand on its extended surface the severe internal pressure which would be brought upon it in the accumulation of enough pressure in the hold to give the vessel the desired buoyancy.

Having thus described my invention what I claim is:

1. The method of raising submerged vessels, which consists in forcing air under pressure into a hold to expel the water, maintaining permanently within the hold a column of water to trap the introduced air in sufficient volume to give the necessary buoyancy to the vessel to cause it to rise, and allowing the trapped air to escape through said column of water in accordance with the reduction in hydrostatic pressure resulting from the rise of the vessel.

2. The method of raising submerged vessels, which consists in forcing air under pressure into a hold to expel the water, maintaining permanently within the hold a column of water to trap the introduced air in sufficient volume to give the necessary buoyancy to the vessel to cause it to rise, and allowing the trapped air to escape through the column of water at a rate sufficient to compensate for the reduction of the hydrostatic pressure on the deck irrespective of the speed of rise of the vessel.

3. In combination with a vessel's hold provided with a hatchway, a hollow open-ended trunk depending a substantial distance into the hold through the hatchway and fastened to the marginal edges of the hatchway, the cross-sectional form and size of said trunk where it is secured, corresponding substantially to the contour and size of the hatchway, and means for the introduction of air under pressure into the hold in the space surrounding the trunk.

4. In combination with a vessel's hold provided with a hatchway, a hollow open-ended trunk depending a substantial distance into the hold through the hatchway, the cross-sectional form and size of said trunk corresponding substantially to the contour and size of the hatchway, means for fastening the trunk detachably to the marginal edges of the hatchway, and means for

the introduction of air under pressure into the hold in the space surrounding the trunk.

5. In combination with a vessel's hold provided with a hatchway, a hollow open-ended trunk depending a substantial distance into the hold through the hatchway, the cross-sectional form and size of the trunk corresponding substantially to the contour and size of the hatchway, clamping devices applied at intervals to said trunk and the marginal edges of the hatchway to fasten the trunk within the hatchway, and means for the introduction of air under pressure into the hold in the space surrounding the trunk.

6. In combination with a vessel's hold provided with a rectangular hatchway, a hollow open-ended trunk of rectangular form in cross-section and of a cross-sectional size substantially similar to that of the hatchway, said trunk depending a substantial distance into the hold and fastened to the marginal edges of the hatchway, and means for the introduction of air under pressure into the hold in the space surrounding the trunk.

7. In combination with a vessel's hold provided with a hatchway, a portable open-ended trunk of a cross-sectional form and size corresponding substantially to the form and size of the hatchway, said trunk being adapted to be entered and fastened in the hatchway so as to depend a substantial distance into the vessel's hold, and guiding members on the trunk adapted to cooperate with the marginal edges of the hatchway in facilitating the positioning of the trunk therein.

8. In combination with a vessel's hold provided with a rectangular hatchway, a portable hollow open-ended trunk of a rectangular form and size in cross-section substantially corresponding to the form and size of the hatchway, said trunk being adapted to be entered and secured in the hatchway so as to depend a substantial distance into the vessel's hold, and guiding plates secured to the sides of the trunk and adapted to cooperate with the marginal edges of the hatchway in facilitating the positioning of the trunk therein.

9. A portable pressure relief trunk for use in raising submerged vessels, said trunk being hollow and open at opposite ends and of a shape and size in cross-section corresponding substantially to the form and size of the vessel's hatchway and adapted to be entered and fastened in the hatchway so as to depend a substantial distance into the vessel's hold, and provided with guiding members arranged to cooperate with the marginal edges of the hatchway in facilitating the positioning of the trunk therein.

10. In combination with a vessel's hold having a hatchway and a hatch coaming

extending upwardly therefrom, a trunk of substantially rigid material permanently open at its two ends and extending within the hatchway in proximity to the inner side 5 of the hatch coaming and depending therefrom a substantial distance into the hold, said trunk being provided at its upper portion with an outwardly projecting marginal

extension seated upon the upper edge of the hatch coaming, and means for clamping 10 said extension down against the said edge to hold the trunk in position.

In testimony whereof, I have affixed my signature hereto.

FREDERICK W. EBELING.
